UNITED STATES PATENT OFFICE.

ELMER E. JENKINS, OF ROCHESTER, MINNESOTA.

BAG-HOLDER.

SPECIFICATION forming part of Letters Patent No. 728,110, dated May 12, 1903.

Application filed August 13, 1902. Serial No. 119,518. (No model.)

To all whom it may concern:

Be it known that I, ELMER E. JENKINS, a citizen of the United States, residing at Rochester, in the county of Olmsted and State of Minnesota, have invented new and useful Improvements in Bag-Holders, of which the following is a specification.

My invention relates to bag-holders; and the object of the same is to design a device 10 of this character which will be simple in construction and efficient in operation.

The novel construction employed by me in carrying out my invention is fully described in this specification and claimed, and illustrated in the accompanying drawings, forming a part thereof, in which—

Figure 1 is a perspective of my device. Fig. 2 is a detail of the stop. Fig. 3 is a detail of a modified form.

Like numerals of reference designate like parts in the different views of the drawings.

In forming my device two integral V-shaped members 1 are employed, which are pivoted at their vertices on a pintle 2. The members 25 1 have arms 3 and 4. The arms 3 are bent at right angles at 5 to form jaws 6, which fit within a bag to hold it open. The jaws 6 have free ends 6^a, which engage and hold the bag against slipping off. The arms 4 form handles for operating the jaws 6 and are apertured at 7 to accommodate links 8, which are connected at one end thereto and at their other ends to a ring 9, which serves as means to suspend the bag-holder and its load. In 35 order to limit the spread of the jaws to prevent bursting the bag, a lug 10 is formed on the vertex of one of the members 1.

In operation the device is hung up by the ring 9, and a bag 11 is engaged on the jaws 6.

In the modified form lugs 12 are formed on the arms 3 and 4 at the bend 5, which lugs

serve to engage the bag to hold it from slipping off.

I do not wish to be limited as to details of construction, as these may be modified in 45 many particulars without departing from the spirit of my invention.

Having described my invention, what I claim as new, and wish to secure by Letters Patent, is—

1. In a bag-holder the combination of two V-shaped members connected at their vertices by a pintle, one arm of each of said members being bent at right angles to the plane of the members to form straight jaws 55 having free ends for engaging a bag, the other arms of said members forming handles, links connected to said handles, a suspension-ring connected to said links, and a stop located to limit the spread of the said jaws, 60 substantially as described.

2. In a bag-holder, the combination of two V-shaped members connected at their vertices by a pintle, one arm of each of said members being bent at right angles to the 65 plane of the V to form straight jaws having free ends for engaging a bag, the other arms of said members forming handles for operating said jaws, a lug formed on the one of said V-shaped members adjacent to the vertex 70 thereof to serve as a stop to determine the spread of the jaws and lugs for engaging a bag, formed on said first-mentioned arms near their points of junction with said jaws, substantially as described.

In testimony whereof I have hereunto set my hand in presence of two subscribing witnesses.

ELMER E. JENKINS.
